UNITED STATES PATENT OFFICE.

CLARENCE V. ROBERTS, OF PHILADELPHIA, PENNSYLVANIA, ASSIGNOR TO ROBERTS & MANDER STOVE COMPANY, OF PHILADELPHIA, PENNSYLVANIA, A CORPORATION OF PENNSYLVANIA.

OVEN STRUCTURE FOR GAS-RANGES.

1,318,802.

Specification of Letters Patent. Patented Oct. 14, 1919.

Application filed July 9, 1918. Serial No. 244,079.

To all whom it may concern:

Be it known that I, CLARENCE V. ROBERTS, a citizen of the United States, residing in Philadelphia, Pennsylvania, have invented 5 certain Improvements in Oven Structures for Gas-Ranges, of which the following is a specification.

One object of my invention is to improve the construction and appearance of an oven 10 of a gas range so that the hinges will not protrude beyond the frame and the frame will have a rounded appearance.

A further object of the invention is to improve the construction of the hinge arrangement of the oven door so that it can be readily raised and lowered, the door coming in contact with a base plate and not swiveled on pivot pins as heretofore.

In the accompanying drawings:

20 Fig. 1 is a front elevation of my improved gas range;

Fig. 2 is a sectional view on the line 2—2,

Fig. 4;

Fig. 3 is a sectional view on the line 3—3,

Fig. 4;

Fig. 5 is a front elevation of one side of the door and frame, showing the hinged portion;

Fig. 6 is a sectional view on the line 5—5,

Fig. 4;

Fig. 6 is a detached perspective view of a portion of the frame;

Fig. 7 is a detached perspective view of one corner of the door;

35 Fig. 8 is a detached perspective view of the cap plate, which is adapted to the frame and incloses the hinged portion of the door; and

Fig. 9 is a view on the same section as Fig. 2, with the door in the open position.

Referring to the drawings, 1 is the oven section of a gas range and 2 is the section having the exposed burners used for ordinary cooking. The oven section, in the present instance, has the main oven section 3 and the broiler section 4. The front frame 5 incloses both portions of the oven section. 6 is the door of the oven section and 7 is the door of the broiler section. Both of these doors, in the present instance, are arranged so as to turn down. The frame 5, as clearly shown in Figs. 5 and 6, has an uninterrupted curved surface, which can be highly polished,

if desired, making an exceedingly attractive range.

55

It has been the general practice either to hinge the doors by exposing the hinges, which project beyond the frame, or to mount the hinged portions in projecting casings. One of the objects of this invention is to 60 conceal the hinged portions and to inclose them within the frame so that they are not exposed to view.

8 and 9 are cap plates, one set for the oven portion and the other set for the 65 broiler portion. The outer surface of each cap plate is flush with the outer surface of the frame 5, as clearly shown in Fig. 5. The lower edge 10 of the oven door 6 rests on an inclined bearing surface 11 of the 70 cross bar of the frame 5, forming a base plate on which the door turns. On each lower corner of the door 6 are pins 12, each of which is adapted to a vertical slot 13 in the rib 14 of the frame so that, as the 75 door moves from the vertical to the horizontal position, the pins 12 will rise up into the slot and the projecting portion 20 of the cap 8 will hold the door in the horizontal position when open. Projecting 80 rearwardly from each of the pins 12 is an arm 15 to which is pivoted an L-shaped plate 16 having a rod 17 secured thereto, which extends through a lug 18 on the frame and mounted on this rod 17 is a coiled spring 19, 85 which tends to counterbalance the door 6. The door, in moving from the closed position, Fig. 2, to the open position, Fig. 9, rides on the portion 11 of the frame 5, while the pin 12 moves upward into the upper 90 portion of the slot 13, the counterbalancing spring allowing for this movement. The spring, when the door is closed, overbalances the door, owing to its position, but, when the door is open to the full extent, as in Fig. 95 9, it overbalances the spring and remains in this position until closed. When the door is being closed, the spring counterbalances the door. The spring may be inclosed in a box, or located in a compartment to protect it from excessive heat so as not to draw the temper of the spring. A weight may be substituted as a full equivalent of the spring, if found desirable.

By this construction, it will be seen that 105 the hinge, or pivot section, of the portions

of the door are in the back of the front surface of the frame and there are no projecting portions of the frame. When the cap plate is in position the entire frame can be plated and polished so as to give the frame an ornamental and attractive appearance.

I claim:

1. The combination in a range, of an oven frame having a continuous outer surface and a bearing plate; a door having laterally projecting pins near the lower portion thereof, the lower surface of said door sliding on the bearing plate of the frame, the pins on said door limiting the movement thereof, and means for balancing the door.
2. The combination in a range, of an oven frame having a continuous unbroken surface; a door mounted in the frame; the lower portion of the door being arranged to slide on the bearing plate forming part of the frame, said frame having a vertical slot at each side; a pin on the door arranged to travel vertically in said slot when moved from the closed to the open position.
3. The combination in an oven, of a frame having a curved outer surface; a door hung at its lower portion to the frame, said door being arranged to move from the open to the closed position on said frame; a pin projecting from each edge of the door at its lower end, said frame having an elongated vertical slot adapted to receive the pin; an arm on each pin; a rod pivoted to the arm and extending through a lug on the frame; a counterbalance spring mounted on the rod

and tending to balance the door; a cover plate mounted in the frame and inclosing the pin, the outer surface of said plate being flush with the surface of the frame so that 40 the surface of the frame, when the plate is in position, will be smooth and uninterrupted.

4. The combination of the frame of an oven having a curved surface and having an 45 opening for the oven, the frame having a recess at each side; a rib in each recess, the lower portion of the rib having an elongated notch; a cover plate arranged to close the recess and having a portion extending 50 in front of the recess; a door mounted in the opening in the frame; a pin at each side of the door extending into the recess of the rib; an arm projecting rearwardly from the pin; and a counterbalance connected to the 55 arm for counterbalancing the door, the door, in moving from the open to the closed position, sliding on the frame and the pin moving vertically in the recess on the rib of the frame.

5. The combination in a range, of an oven frame; a door mounted in the frame; the lower portion of the door being arranged to slide on the bearing plate forming part 65 of the frame, said frame having a vertical slot at each side; and a pin on the door arranged to travel vertically in said slot when moved from the closed to the open position.

In witness whereof I affix my signature. 70

CLARENCE V. ROBERTS.
